UNITED STATES PATENT OFFICE.

CHARLES IFLAND, OF CHICAGO, ILLINOIS.

HORSE-COLLAR.

SPECIFICATION forming part of Letters Patent No. 339,892, dated April 13, 1886.

Application filed December 28, 1885. Serial No. 186,886. (No model.)

To all whom it may concern:

Be it known that I, CHARLES IFLAND, a subject of the Emperor of Germany, residing at Chicago, in the county of Cook and State of Illinois, have invented certain new and useful Improvements in Horse-Collars, of which the following is a specification, reference being had therein to the accompanying drawings.

This invention relates to collars and hames that can be adjusted to fit different-size horses; and it has for its object to produce such a collar and hame that is strong and durable, is readily placed and secured over the horse's neck, and that will not chafe the skin, but will make a comfortable fit.

My invention consists of certain novel combinations of parts, as will be described and claimed.

In the accompanying drawings, Figure 1 represents an elevation of the hame and collar complete; Fig. 2, a vertical cross-section through the center of the upper portion; Fig. 3, a sectional elevation of the zinc shield detached; Fig. 4, a sectional view of the hame-locking hasp; Fig. 5, a similar view of the hame-locking stud; Fig. 6, a cross-section on line 6 6 in Fig. 1, and Fig. 7 a cross-section on line 7 7 in Fig. 1.

Corresponding letters in the several figures of the drawings designate like parts.

A A' denote the upper sections of the hame-bars, hinged together at *a*, and B B' are the lower sections of such hame-bars. These bars are cast of metal, to be very light, and are longitudinally corrugated to the shape in cross-section somewhat like the letter W. The lower sections, B B', slide under the upper sections, A A', so as to be overlapping therewith, and to near the upper end of each lower section, B B', is cast a loop, *b*, through the central hub of which is tapped a set-screw, *c*, having an eyed head, *d*, with a ring, *C*, that is the handle for turning such screw, which rings *C* at the same time form the terrets. The upper sections, A A', have secured plates *D*, provided with a series of sockets, *e*, either one of which will engage the point of a set-screw, *c*, for clamping and rigidly holding the sections A B on any desired position of lengthening or shortening the hame-bars best fitting the horse's neck. The lower extremity of side

bar B has secured by a rivet, *f*, a hasp, *E*, that has three (more or less) holes, and the lower extremity of side bar B' has a stud, *g*, that will enter any one of the three holes of hasp *E*, and has a slotted hole for a key, *h*, connected to the hasp *E* by a strap, *i*, which key *h* will secure the hasp *E*, thereby fastening the hame and collar upon the horse's neck on dimension 55 best fitting. In a pending eye rigid with section B' is linked a ring, *F*, for coupling the neck-yoke strap or chain. The collar *G* is made of leather stuffed with hair, and secured against the inner face of the sections B B' of 65 the hame-bars by screws *j*, passed through holes in the edges of such hame-sections and engaging with screw-nuts *K*, inserted into such collar. This collar *G* is formed of two sections overlapping at their bottom ends when 70 the hame is fastened around the horse's neck, but extending at the top only under shield *H*. A link, *l*, made of flat iron, is placed around the hinge *a*, that connects the hame-sections A A', and into this link is tapped the standard *m* of a bell, *n*, when the hame and collar is used on street-railway horses; or a check-rein hook may be screwed on instead. To link *l* is also coupled a buckle or ring, *o*, for securing the back-strap of the harness. A 75 saddle-shaped shield, *H*, made of sheet-zinc, and having a loop, *p*, formed to its top, is secured under hinge *a* by a strap, *q*, passed through slots in link *l*, and a pad or bolster, *r*, is placed intermediate of such hinge *a* and loop *p*, and is also held in position by strap *q*. The shield *H* being smooth, and zinc being a 85 cooling and non-irritating metal, it will not chafe nor cause soreness of the skin from the pressure and motion of the hame and collar 90 on the top of the horse's neck.

I I are the tug-clips, that may be of any usual construction.

I am aware that collars have been formed of metal overlapping sections held together by 95 screws passed through openings in each; also, that it is old to use a zinc shield with horse-collars, and also that a perforated stud has been used in connection with a hasp and retaining-strap, and therefore I make no claim 100 to such constructions; but

What I claim is—

1. The hame-bars of a horse-collar, composed each of two sections overlapping each

other, and one section provided with a loop, and a set-screw mounted in such loop, and the other with a plate having a series of sockets, substantially as and for the purpose set forth.

5 2. The combination, with sections A A', hinged at *a*, of link *l*, shield *H*, provided with loop *p*, and strap *q*, passed through the loop and link, as set forth.

3. The combination, with sections A A',
10 hinged at *a*, of link *l*, shield *H*, provided with loop *p*, strap *q*, passed through the link and loop, and interposed padding *r*, as set forth.

4. The combination, with sections B B', plate D, and sockets *e*, of sections A A', loops *b*, and set-screws *c*, as set forth.

In testimony whereof I affix my signature in presence of two witnesses.

CHARLES IFLAND.
